CLAIM

The ornamental design for an edible pet chew, substantially as shown and described.

DESCRIPTION

FIG. 1 is a perspective view of the front end, left side and top of the edible pet chew, showing my new design;

FIG. 2 is a top plan view thereof;

FIG. 3 is a side elevational view of the left side thereof;

FIG. 4 is a bottom plan view thereof;

FIG. 5 is a side elevational view of the right side thereof;

FIG. 6 is a front elevational view of the edible pet chew; and,

FIG. 7 is a rear elevational view thereof.
